INVENTOR

UNITED STATES PATENT OFFICE

113,605

DESIGN FOR A BEDSPREAD

Gertrude I. Linde, New York, N. Y., assignor to Harriette A. Lawson, Signal Mountain, Tenn.

Application January 18, 1939, Serial No. 82,424

Term of patent 3½ years

To all whom it may concern:

Be it known that I, Gertrude I. Linde, a citizen of the United States, residing at New York city, county of New York, and State of New York, have invented a new, original, and ornamental Design for Bedspreads, of which the following is a specification, reference being had to the accompanying drawing, forming part thereof.

The figure of the drawing is a plan view of the bedspread showing my design.

I claim:

The ornamental design for a bedspread, substantially as shown.

GERTRUDE I. LINDE.
